LIGHTING FIXTURE

Joseph Novin, Bronx, N. Y.

Application July 27, 1948, Serial No. 147,791

Term of patent 14 years

(Cl. D48—23)

To all whom it may concern:

Be it known that I, Joseph Novin, a citizen of the United States, residing at the Bronx, in the county of Bronx and State of New York, have invented a new, original, and ornamental Design for a Lighting Fixture, of which the following is a specification, reference being had to the accompanying drawing, forming part thereof.

Figure 1 is a perspective view of a lighting fixture, showing my new design; and

Figure 2 is a fragmentary sectional view of the lower portion.

I claim:

The ornamental design for a lighting fixture, as shown.

JOSEPH NOVIN.
